MOLD FOR RAIL WELDING UNDER TRAFFIC

Filed Sept. 5, 1931

INVENTOR

Charles D. Young

BY HIS ATTORNEY

Charles D. Young

UNITED STATES PATENT OFFICE

CHARLES D. YOUNG, OF CHICAGO, ILLINOIS

MOLD FOR RAIL WELDING UNDER TRAFFIC

Application filed September 5, 1931. Serial No. 561,350.

The invention relates to a novel form of mold for effecting the welding of railway rails by superheated molten metal, such as produced by the alumino-thermic reaction; 5 said mold being adapted to be applied to the rail ends in such manner as to permit passage of traffic thereover during the welding operation.

The invention is illustrated in the accompanying drawings, in which:—

Fig. 1 is a transverse section of the improved mold as applied to a T-rail.

Fig. 2 is a similar view showing a slightly modified form of mold.

Referring to the drawings, 1 indicates the end of one of the rails to be welded, and 2 either a projection on the end of the rail head formed by undercutting the other portions of the rail or an insert applied between the ends of the rail heads, as is common practice in effecting pressure welds between the rail heads and fusion welds between the other parts of the rails. The ends of the rails are enclosed in a refractory mold composed of two half mold sections 3 and 4 which extend up to a point approximately in line with the tread surfaces of the rails, these mold sections, when clamped to the rail ends, defining a mold cavity 5 to receive the superheated molten metal which is delivered to the mold through a pouring gate 6 located in one of the mold sections. The other section is provided with a vent or riser 7, which communicates with a lateral overflow channel 8 formed in the top surface of the mold section and located slightly below the level of the rail treads, so that any excess of molten metal in the riser 7 will escape by way of this channel and will not overflow the tread surface of the rails with the consequent harm thereto.

Formed in the mold section 3 on the tread side of the rails is a depression 10 adapted to clear the wheels of traffic while the mold is in place, and, in order to seal this depression 10 against the entrance of molten metal, the mold section is provided with a tongue or extension 11 below the depression, which tongue is in sealing engagement with the gauge side of the rail heads. In the event that the tongue 11 does not make a tight joint

with the heads of the rails, a suitable luting may be applied at this area of engagement between the tongue and the heads of the rails.

In Fig. 2, the construction of the mold sections is substantially the same as in the preceding figure, except that the pouring gate and the riser are formed as a single opening 6' through the top of the mold section 4' communicating with the mold space 5, the overflow channel 8 being formed in the top 63 of the mold section to discharge any surplus metal which might tend to overflow the treads of the rails in the same manner as described in connection with the mold shown in Fig. 1. In this modified form of Fig. 2, 65 the other mold section 3' is provided with a vent 15 which is disposed laterally of and below the depression 10 provided in the top of the section to clear the wheels of traffic, and, as in Fig. 1, communication between said depression 10 and the mold cavity is prevented by the tongue or extension 11' which engages the gauge face of the rail heads.

In the case of welding T-rails, the part 2, 71 whether the same be a projection on the face of one rail end or a separate insert, should extend to substantially the full depth of the gauge face of the rail head, as shown, in order to assure a sealing contact with the extension or tongue 11 of the mold which separates the depression 10 from the mold cavity.

From the foregoing description, it will be apparent that a mold embodying the characteristics as set forth may be readily clamped in position about the ends of the rails to be welded and will not interfere with the passage of traffic over the joint during the preparation for and the actual welding operations.

What I claim is:

1. A mold for welding rails by superheated molten metal, comprising half mold sections adapted to embrace the rail ends, said sections being provided with pouring and venting openings, the section on the gauge side 95 of the rails having a depression to clear the wheel flanges and also a tongue to engage the gauge faces of the rails to separate and seal the mold cavity from said depression.

2. A mold for welding rails by superheated

100

101

molten metal, comprising half mold sections embracing the rail ends, one section having a pouring gate and the other section having a vent provided with a lateral overflow channel slightly below the level of the rail tread surface.

3. A mold for welding rails by superheated molten metal, comprising half mold sections embracing the rail ends, the section on the gauge side of the rails having a depression to clear the wheel flanges, a tongue at the bottom of said depression to engage the gauge faces of the rails to separate and seal the mold cavity from said depression, and a vent extending laterally of and below said depression, the other section having a combined pouring gate and riser provided with a lateral overflow channel slightly below the level of the rail tread surfaces.

20. In testimony whereof I affix my signature.

CHARLES D. YOUNG.
